United States Patent Office

Des. 229,548
Patented Dec. 11, 1973

229,548

CONTAINER FOR LIQUIDS

Arnold H. Kranz, Chicago, Ill., assignor to Helene
Curtis Industries, Inc., Chicago, Ill.

Filed Aug. 12, 1971, Ser. No. 171,414

Term of patent 14 years

Int. Cl. D9—01

U.S. Cl. D9—169

FIG. 1.

FIG. 2.

FIG. 3

FIG. 1 is a perspective view of a container for liquids embodying my new design;

FIG. 2 is a top plan view thereof; and

FIG. 3 is an elevation view as seen from the rear of FIG. 1.

I claim:

The ornamental design for a container for liquids, substantially as shown.
